UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

HOPPER-CAR.

1,121,165.

Specification of Letters Patent. Patented Dec. 15, 1914.

Application filed February 21, 1914. Serial No. 820,36.

To all whom it may concern:

Be it known that I, ANDREW CHRISTIANSON, a citizen of the United States, and resident of Butler, in the county of Butler and State of Pennsylvania, have invented a new and useful Improvement in Hopper-Cars; and I do hereby declare the following to be a full, clear, and exact description thereof.

My invention relates to hopper-cars.

10 The object of my invention is to improve the construction of these hopper-cars in certain ways, so as to obtain a more durable and stronger construction, to enable the car to sustain the increased loads and the necessarily greater wear and tear to which said cars are subjected by reason of such increased loads.

To these ends my invention comprises the novel features hereinafter set forth and 20 claimed.

In the accompanying drawings, Figure 1 is a side elevation of a portion of a hopper-car embodying my invention; Fig. 2 is a view plan and view section on the line 25 2—2 Fig. 1; Fig. 3 is a vertical section of portion of a hopper-car; Fig. 4 is a section on the line 4—4, Fig. 3; Fig. 5 is a section on the line 5—5, Fig. 3, and Fig. 6 is an enlarged detail.

30 In the drawing, the numeral 2 designates the side-plates and 3 the inclined end-plates of a suitable hopper-car connected by angles and braced in the ordinary manner, which it is not deemed necessary to describe in detail.

35 The center-sills 4 consist of channel-beams with the flanges inwardly turned. The inside hopper-sheets 5 are secured to the center-sills 4, and the upper ends of said hopper-sheets are inclined as at 6, to form the 40 central ridge extending from one inclined end-plate 3 to the other, and riveted thereto.

The outside hopper-sheets 7 are riveted to the side-plates 2 of the car, and the inside joint-strips 8 at their lower ends overlap 45 the upper ends of the hopper-sheets, and are riveted thereto as clearly indicated in Fig. 4.

The bottom of the car is divided into a series of hoppers 9 on each side of the center-sills, which are made up of the inside 50 hopper-sheets 5, the outside hopper-sheets

7 and the inclined hopper-plates 10. The vertical diaphragm plates 11 extend from the outside hopper-sheets to the inside hopper-sheets and to a point above the same, 55 said plates being flanged as at 12 and riveted to the side plates 2 as indicated in Fig. 2.

Cross-braces 13 made up of angles 14 are secured to the upper ends of the vertical plates 11, and said angles have at their ends 60 the flanges 14 which are riveted to the side-plates. The sloping surfaces of these braces prevent the collection of the ore, coal, or other material contained within the car, and said braces act to stiffen and strengthen the 65 sides against inward or outward bulging. Like braces 16 extend from side to side of the car at a point near the top thereof.

Riveted or otherwise secured to the incline hopper-plates 10 are the stiffening bars 70 17, which extend below the center-sills transversely of the car. These bars may be of any suitable form, either rolled or pressed, those illustrated being in the form of angle-bars. Braces 18 are riveted to the flanges 75 19 of the angle-bars 17 at suitable intervals, said braces acting to strengthen the inclined hopper-plates against the strains of the load. These brace-plates 18 may be formed by pressing and have the strengthening ribs 80 20 formed therein. The hinged lugs 21 are secured to the angle-bars 17 at suitable intervals, and from these hinge lugs the doors 22 are swung. These doors are arranged in pairs and may be operated by any suitable 85 door operating mechanism.

By having the inclined hopper-plates 10 extending down below the center-sills, and the braces or stiffening members 17, extending along the lower edges of said hopper- 90 plates, practically from one end to the other, I obtain a very much more rigid construction and the hopper-plates are greatly stiffened and strengthened.

What I claim is:

1. In a hopper-car, the combination of the center-sills, the inside hopper-sheets, inclined hopper-plates extending below the center-sills, and stiffening members secured to said inclined hopper-plates below said 100 center-sills and extending through said hopper-sheets.

2. In a hopper-car, the combination of center-sills, inside hopper-sheets, inclined hopper-plates extending below the said center-sills, stiffening angle-bars connected to 5 said hopper-plates below said center-sills, and extending through said hopper-sheets, and braces connecting said angle-bars.

In testimony whereof, I the said ANDREW CHRISTIANSON, have hereunto set my hand.

ANDREW CHRISTIANSON.
